UNITED STATES PATENT OFFICE.

SAMUEL T. NEWMAN, OF DANBURY, CONNECTICUT, ASSIGNOR TO CHARLES H. MERRITT, OF SAME PLACE.

HAT-TRIMMING MACHINE.

SPECIFICATION forming part of Letters Patent No. 449,911, dated April 7, 1891.

Application filed June 21, 1890. Serial No. 356,228. (No model.)

To all whom it may concern:

Be it known that I, SAMUEL T. NEWMAN, of Danbury, in the county of Fairfield and State of Connecticut, have invented a certain 5 new and useful Improvement in Hat-Trimming Machines, of which the following is a specification.

My improvement relates to machines which are employed for trimming the brims of hats. 10 These machines are commonly termed "rounding-jacks" or "hat-trimming machines."

I will describe a machine embodying my improvement and then point out the novel features in the claims.

15 In the accompanying drawings, Figure 1 is a sectional elevation of a machine embodying my improvement. Fig. 2 is a vertical section of certain parts, taken at the plane of the dotted line $z z$, Fig. 1.

20 Similar letters of reference designate corresponding parts in both figures.

A designates the frame of the machine. It may be of any suitable construction and material.

25 B designates a support for a hat-body to be trimmed. As here shown, it consists of a body b , a number of arms b' b^2 b^3 , supported by the body and made adjustable toward and from a common center, and segmental pieces 30 attached to the upper ends of said arms.

The body-piece of the hat-support is fastened to and carried by a shaft C, journaled in a bearing a , provided in a cross-piece or bed a' of the machine-frame. It has affixed 35 to its lower end a gear-wheel c , which meshes with a gear-wheel c' , affixed to a stud c^2 , which is supported by the frame A. A bevel gear-wheel c^3 is affixed to the gear-wheel c' and engages with a bevel gear-wheel c^4 , which is

40 loosely mounted upon a shaft E. The shaft E is secured in the frame A of the machine. It is not intended to rotate. On it are loosely mounted a fly-wheel e , a belt-pulley e' , and a driving-belt pulley e^2 . The fly-wheel and the 45 two belt-pulleys are locked together by cross-pins, which rotate in unison. The belt, which is fitted to the driving-pulley e^2 , transmits to the machine power from any source. The belt-pulley e' transmits power through a belt

e^3 to a belt-pulley f , which is affixed to a counter-shaft F.

The machine is intended to cause but a single rotation of the hat-body and then stop. To enable it to do this I combine with the belt-pulley e^2 and the bevel gear-wheel c^4 a clutch. 55 and also combine with the latter a stop, whereby the operation of the machine will be terminated periodically. The clutch consists of a number of pins e^4 , which are fitted in cavities formed in the driving-belt pulley e^2 60 in positions parallel with the axis of the latter. These pins e^4 are shouldered. Their larger ends project from the pulley e^2 toward the bevel gear-wheel c^4 , while their smaller ends extend through the backs of the cavities 65 in the pulley e^2 , which accommodate them, and are furnished beyond the back of said cavities with cross-pins, whereby they are prevented from becoming detached from the pulley. Coiled springs surrounding the 70 smaller portions of the pins e^4 and within the cavities in the pulley e^2 tend to force the pins e^4 toward the bevel gear-wheel c^4 .

The bevel gear-wheel c^4 is provided with a cavity, in which a pin c^5 is fitted in a position parallel with the axis of the wheel and at such a distance from the axis that this pin may engage with one of the pins e^4 of the pulley e^2 . The pin c^5 is forced toward the frame of the machine by means of a spring, which is coiled 75 around it and is designed to have a bearing at one end against the bevel-wheel c^4 and at the other end against a head with which the pin is provided.

In the machine-frame is a recess, into which 80 the head of the pin c^5 may be forced by the spring. When the pin is forced into this recess, the gear-wheel c^4 will be locked to the frame and the machine stopped. Once in each rotation of the bevel gear-wheel this will 85 occur. When the pin c^5 is moved longitudinally to disengage it from the frame A, it will project into the path of the pins e^4 , and the first one of these pins e^4 which reaches it will 90 transmit motion through it to the bevel gear-wheel c^4 , and in this way the machine will 95 operate. As soon as the pin c^5 comes opposite its recess in the frame it will move lon-

itudinally out of engagement with that one of the pins e^4 with which it was previously engaged. Hence it will no longer be in condition to derive motion from the driving-belt 5 pulley e^2 , and will, moreover, be stopped by engagement with the frame A.

E' is a lever fulcrumed to the cross-piece or bed a' of the machine-frame. At one end it is bent to extend into the recess which is provided in the machine-frame for the reception of the pin c^5 . This end is moved outwardly 10 away from the recess by a spring e^6 as far as it is permitted to move by a stop-pin e^7 , which is inserted in the cross-piece or bed a' . The 15 other end of this lever is provided with a handle and extends into a position convenient for the operator of the machine. When this lever is oscillated against the resistance of the spring e^6 , it may be made to force the pin c^5 20 out of its recess in the machine-frame A and into the path of one of the pins e^4 .

The advantage of providing a number of pins e^4 is so that the driving-pulley e^2 may more readily engage with the bevel gear-wheel c^4 . A yielding connection between the pins e^4 and the driving-belt pulley e^2 is advantageous, because if the lever E' should force the pin c^5 toward the driving-belt pulley e^2 when one of the pins e^4 happens to be 25 opposite said pin c^5 breakage will be obviated by the longitudinal yielding of the pin e^4 , and after that the next pin e^4 will engage with the pin c^5 .

J designates a hold-down having a body 35 piece which has a swiveling connection with a vertically-movable slide K, and having combined with it outwardly-movable arms, which coact with the segmental pieces of the hat-holder. The slide K can be depressed by a 40 treadle L, connected with a lever G by means of a cord g , passing around guide-pulleys g^1 g^2 g^3 g^4 . The lever G is slotted at the free end to connect with a pin projecting from the slide K. A counter-balance k may be combined with the slide K. When a hat is put 45 in a holder, the hold-down is depressed by means of the treadle to secure it therein.

D' D^2 designate cutters, which are employed to trim the hat-brim. They are shown as 50 supported in a frame D, which is affixed to a slide D^4 , that is fitted to a slide D^5 , so as to be adjustable toward and from the center of the hat-holder. The slide D^5 is in turn fitted to a slide D^6 , so as to be adjustable relatively thereto toward and from the center of the hat-holder. A screw d^{28} clamps the slides D^5 D^6 55 together, and a screw d^{29} serves to clamp the slides D^4 D^5 together.

The cutters are shown as mounted upon rotary shafts, the upper of which is normally elevated by springs d^4 from the other, but is, when the cutters are to operate, depressed by a lever D^3 , which is swung downward by the lever G, and in its descent causes a gear-wheel d^{19} , affixed to the shaft of the cutter D^2 , 60 to engage with a gear-wheel d^{14} , with which

the shaft of the lower cutter D' is provided. The upper cutter will then derive rotary movement from the shaft of the lower cutter. The shaft of the lower cutter is driven by a 70 belt d^{12} from the shaft F, which is journaled in the machine-frame.

The slide D^6 has a horizontally-extending portion and a downwardly-extending portion. The horizontally-extending portion is provided on the under side with rollers d^{23} , which are fitted to studs extending from lugs formed with the slide, and travel along rails or shoulders d^{24} , with which the machine-frame is provided. The downwardly-extending portion 75 of the slide D^6 is preferably provided with a roller d^{25} , which bears against a cam H. This cam may advantageously be made of wood. It is mounted upon a shaft I, which is arranged in line with the shaft C and derives 80 rotary motion from the latter.

The cam H is to have the same outline as that to which the brims of hat-bodies are to be trimmed, although it need not be of the same size as the edge of the brims when 85 trimmed. As this cam rotates it moves the slide D^6 , and consequently the slides D^5 D^4 and cutter-carrying frame D, relatively to the center of the hat-holder. As shown, it only moves these parts outwardly, and a spring D^7 , 90 which, as here shown, acts against the slide D^6 , moves them inwardly. This spring, as shown, at one end surrounds a pin that projects outwardly from the horizontal portion 95 of the slide D^6 and extends into a pocket d^{26} , 100 with which the machine-frame is provided. The spring bears against a plate, which is attached to a screw d^{27} , that is longitudinally adjustable in the pocket. Hence by manipulating this screw the tension of the spring 105 may be varied. The pocket, as here shown, is made integral with a bracket which is fastened to the machine-frame.

Obviously different hat-bodies will require cams H of different shape, and owing to this 110 I provide for readily substituting one such cam for another. A simple way of affording this provision consists in constructing the upper end of the shaft I to interlock with the lower end of the shaft C and so supporting 115 the shaft I that it may be moved vertically to disengage it from and re-engage it with the shaft C. The shaft I has its upper end made polygonal, and the shaft C is provided with a socket capable of engaging with the polygonal 120 end of the shaft I. This socket is not in the present instance formed in the shaft C, but consists of a collar C', which is attached to the shaft C. This collar is shown as fastened to the shaft C indirectly by being secured 125 through the agency of screws to the gear-wheel c, which is secured to the said shaft.

The shaft I is supported in a bearing I', 130 which is provided in a cross-piece of the machine-frame, and at the lower extremity has a step bearing in a sleeve I', that is pivotally connected by a pin i with a lever I'. This

lever I^3 is fulcrumed by a pin i' to a bracket i^2 , secured to a cross-piece of the machine-frame. Between the ends it is slotted or bifurcated to embrace the sleeve I^3 , and this portion is connected by the pin i to said sleeve. The other end of the lever I^3 has a handle, whereby it may be swung up and down to raise and lower the shaft I . This end of the lever may, by a slight lateral movement, be engaged with and disengaged from a hook i^3 , which is fastened to the machine-frame. When the lever is engaged with this hook, it will support the shaft I in a position to maintain engagement with the shaft C . After the disengagement of the lever from the hook the lever may be lowered to disengage the shaft I from the shaft C . After this the cam H may be lifted off the polygonal end of the shaft I with which it interlocks, and it may be replaced by a different cam, after which the shaft I will be elevated again to engage with the shaft C .

M designates a chalk-holder. As here shown, it consists of a lever fulcrumed by a pin m to a stationary part of the machine-frame and having a socket m' , which holds a piece of chalk. By oscillating the lever the chalk may be brought in contact with the under side of the brim of a hat-body. The socket for the chalk has preferably combined with it a screw m^3 , which may serve to cause the chalk to project more or less. Normally the lever of the chalk-holder rests upon a stop-pin m^2 .

The socket m' of the chalk-holder is shown as formed with a plate m^4 , which has a sliding connection with the lever M . In this way the chalk may be adjusted to act on the brim nearer to or farther from the crown. If the cross-pin m^2 were elevated a little, so as to move the lever M into a horizontal position, the sliding section m^4 could be moved lengthwise to mark upon the lower end of the under side of the brim without any operation of the lever M . In this case the lever would have to be shortened at the end which is the nearer to the hat-holder, so as to allow of the adjustment of the chalk beyond the circumference of the brim.

What I claim as my invention, and desire to secure by Letters Patent, is—

1. In a hat-trimming machine, the combination of a holder for hat-bodies, a cutter, a support for the cutter movable toward and from the hat-body, a cam for imparting movement to the cutter-support, and a longitudinally-movable shaft to which said cam is detachably connected, substantially as specified.

2. In a hat-trimming machine, the combination of a holder for hat-bodies, a cutter, a support for the cutter movable toward and from the hat-body, a cam for imparting movement to the cutter-support, and a longitudinally-movable shaft, upon the upper end portion of which said cam is arranged, substantially as specified.

3. In a hat-trimming machine, the combination of a holder for hat-bodies, a cutter, a support for the cutter movable toward and from the hat-body, a cam for imparting movement to the cutter-support in one direction, means independent of the cam for moving the cutter-support in the other direction, and a longitudinally-movable shaft, upon the upper end portion of which said cam is arranged, the said cam and shaft being constructed to interlock, so that the cam may be readily removed and another substituted for it, substantially as specified.

4. In a hat-trimming machine, the combination of a holder for hat-bodies, a cutter, a support for the cutter movable toward and from the hat-body, a cam for imparting movement to the cutter-support, a shaft upon which said cam is mounted, and a driving-shaft arranged in line with the cam-shaft and constructed to interlock therewith, one of said two shafts being supported to have a lengthwise movement whereby it may be engaged with and disengaged from the other, substantially as specified.

5. In a hat-trimming machine, the combination of a holder for hat-bodies, a cutter, a support for the cutter movable toward and from the hat-body, a cam for imparting movement to the cutter-support in one direction, means independent of the cam for moving the support in the opposite direction, a vertical shaft having a polygonal end upon which said cam is arranged and with which it interlocks, a driving-shaft arranged above the cam-shaft and constructed to interlock with the latter, a bearing through which the cam-shaft may slide longitudinally, a step-bearing for the lower end of said cam-shaft, and means for causing a longitudinal movement of the shaft and supporting the same, substantially as specified.

6. In a hat-trimming machine, the combination of a holder for hat-bodies, a cutter, a support for the cutter movable toward and from the hat-body, a cam for imparting movement to the cutter-support, a vertical shaft having a polygonal end upon which said cam is arranged and with which it interlocks, a driving-shaft arranged above the cam-shaft and constructed to interlock with the latter, a bearing through which the cam-shaft may slide longitudinally, a step-bearing for the lower end of said cam-shaft, and means for causing a longitudinal movement of the cam-shaft and supporting the same, substantially as specified.

7. In a hat-trimming machine, the combination, with a hat-holder, of a chalk-holder consisting of a lever fulcrumed to a stationary part of the machine, a slide adjustable lengthwise of the lever, a chalk-socket carried by the slide, and a screw projecting through an opening in the lower end of the socket and serving when manipulated to adjust the chalk, substantially as specified.

8. In a hat-trimming machine, the combination, with a hat-holder, of a chalk-holder consisting of a lever fulcrumed to a stationary part of the machine, a chalk-holder carried by the lever, and a screw projecting through an opening in the lower end of the chalk-holder socket, serving when manipulated to adjust the chalk, substantially as specified.

In testimony whereof I have signed my name to this specification in the presence of two subscribing witnesses.

SAMUEL T. NEWMAN.
